United States Patent

Des. 235,291
Patented June 10, 1975

235,291

DISPLAY CASE

Jerry Shaw, 50 W. Fairlawn Blvd., and Samuel G. Solitt,
2121 Brookshire Road, both of Akron, Ohio 44313

Filed July 3, 1973, Ser. No. 376,138

Term of patent 14 years

Int. Cl. D6—04

U.S. Cl. D6—127

FIG. 1

FIG. 2

FIG. 3

FIG. 1 is a front perspective view of a display case showing our new design;

FIG. 2 is a front elevational view; and

FIG. 3 is a left side elevational view, the right side being a mirror image thereof.

The rear of the display case is plain and unornamented.

We claim:

The ornamental design for a display case, as shown and described.
